UNITED STATES PATENT OFFICE

LAURENCE E. BLOOD, OF BOSTON, MASSACHUSETTS, ASSIGNOR TO S. A. WOODS MACHINE COMPANY, OF BOSTON, MASSACHUSETTS, A CORPORATION OF MASSACHUSETTS

FEED FOR WOODWORKING MACHINES

Application filed January 23, 1928. Serial No. 248,635.

This invention relates to feeding mechanisms for woodworking machines, such, for example, as molders, and the object is to provide an improved mechanism for separating 5 pieces of wood from a pile and advancing them in succession for the operation of the cutter heads of the machine thereon.

My invention will be well understood by reference to the following description of a preferred embodiment thereof shown by way of example in the accompanying drawings, wherein:

Fig. 1 is a side elevation of the feeding mechanism;

Fig. 2 is an end elevation as seen from the right of Fig. 1; and

Figs. 3 and 4 are fragmentary and partly diagrammatic plan sections through the magazine in a plane slightly above the bed.

The embodiment of my invention shown by way of example in the accompanying drawings operates to feed out the bottom board of a pile and is adapted to maintain a continuous feed as long as the supply lasts. I herein 20 use the word "board" not in the technical sense but in a generic sense and the pieces fed may be relatively large and heavy and yet may be handled by the mechanism disclosed.

Referring to the drawings, on the bed 7 25 of the woodworking machine a suitable magazine is provided to receive a vertical pile of boards which may embody a fence 9 and a relatively adjustable fence (see Figs. 3 and 4) comprising a base 10 and posts 11, the adjustment providing for the accommodation of pieces of different widths. A front wall or fence 13 extends inward from the fence 9 and the lower end thereof is spaced from the table 7 (see Fig. 2) to provide an opening 15 30 through which the lowermost board of the pile may be discharged endwise by suitable mechanism such as that about to be described.

As the board leaves the magazine it is fed to a pair of fast running rolls comprising a bed roll 45 17 and a top roll 19 which grasp it and feed it on into the machine. My invention more particularly relates to the means for feeding out the boards which lie at the bottom of the pile in spite of the weight of the overlying 50 boards thereon and the strong frictional re-

sistance caused by the usually rough surface of these boards, the mechanism being adapted to maintain an uninterrupted feed of one board after another without substantial pauses in the feeding operation so that a continuous supply of stock passes through the machine. 55

In the embodiment of the invention shown the pile of boards in the magazine rests upon a driven feed roll 20 projecting through the bottom of the magazine. Driven feed rollers are also provided for operating on the edges of the bottom board, and I have herein shown three vertical rolls 21 located along the fence 9, the first and last of which are 60 driven. Suitable means are provided for pressing the board in driven relation to these rolls, such means being organized to insure effective action of the driven rolls 21 and also to permit the boards automatically to 65 move one after another into cooperation with these driving rolls as soon as the preceding board has left the magazine. For this purpose I provide means for pressing the lowermost board against the rolls 21 which will 70 effect a rapid variation of the pressure of the work thereagainst. It will be understood that if a driven roll of this character begins to slip while in contact with the work, it will 75 continue to slip unless the pressure conditions are changed. I therefore prefer to provide means which are effective to deliver a rapid recurrence of percussive blows against the board which will insure that the board will be moved over into driven relation to 80 the rolls 21 as a mere steady push could not effectively do, and also will effect at each blow an increase in the effective pressure conditions which will insure the rolls 85 acting. 90

I herein provide opposing the rolls 21 a shaft 23 adapted to drive a feed roll 25 of generally disc-like form (see Figs. 3 and 4) cut away along one or more chords and adapted to rotate substantially in the plane 95 of the bottom board in the magazine. The shaft 23 is mounted on a frame turning on trunnions 27 in a carriage 29, here shown as adjustably mounted on the under side of the table 7 to permit the mechanism as a whole 100

to be adjusted when the posts 11 are adjusted and the roll 25 is resiliently held in an inward position toward the opposed rolls 21 by means of the spring 31, best seen in Figs. 3 and 4, the arrangement permitting the shaft to swing about the trunnions and the feeding roll 25 to move away from the rolls 21 when necessary.

The normal position of the shaft 23 with the spring unstressed is such that, when in its rotation (see Fig. 3) a straight sided portion 33 thereof extends longitudinally of the machine, the roll lies outward of the magazine, leaving it unobstructed so that a board 15 may gravitate down over the face of the rolls 21 between the same and the roll 25 to take the place of one fed out. As the roll 25 turns, however, the adjacent peripheral portion 35 will project inwardly of the boundaries of the magazine (Fig. 4) and will deliver a diagonal hammer blow against the edge of the board at the bottom of the pile which will serve to press the same against the opposed feed roll 21 and will also have a component or forward feeding movement. In delivering this blow the head and its shaft will normally yield against the spring 31. This hammer blow may be several times repeated as the board is fed forward to the left 20 in the figures, depending upon the various resistances which may impede the delivery from the pile of that particular board. Thus, if in a given case this board and the one above it were particularly firmly locked on 25 account of the rough surfaces thereof, a greater resistance would be encountered than in the case of relatively smooth and straight stock.

By way of example, in the case of a fast feed machine the shaft 23 may be rotated about one hundred revolutions per minute and with two peripheral portions 35 as shown a number of blows will be struck each second. This arrangement not only insures 40 driving the bottommost board laterally against a feed roll 21 and provides for maintaining it pressed thereto but causes a variation in the pressure conditions. For instance, if the rolls have started to feed the board but 45 due to some resistance the rolls 21 commence to slip, at the next blow struck by the roll 25 there will be a definite increase of the pressure due to the force exerted in overcoming the inertia of the spring 31 necessary 50 to permit the peripheral portions 35 of the roll to pass and this increase in pressure will permit the rolls 21 to grip the board and feed it forward again.

The parts herein described may conveniently 55 be driven in the manner indicated in Figs. 1 and 2. A belt 37 from a suitable power shaft drives the shaft of bed roll 17 and a run of this belt may drive the shaft of a bevel gear 39 meshing with a bevel gear 41 on shaft 23, the axis of trunnions 21 lying in the plane of

engagement of the bevels to permit the yielding of the shaft. At the further side of the machine a chain 40 on the shaft of roll 17 may drive (see Fig. 2) sprocket 41 on the shaft of roll 19, which shaft also carries a sprocket 43 engaging with a chain 45 which drives the sprockets 47 on short shafts 49 which carry bevel gears 51 engaging bevel gears 53 on rolls 21.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

Claims—

1. A feed for a woodworking machine comprising, in combination with a magazine to receive a pile of boards and having an opening for the endwise discharge therefrom of the bottom board, a driven feed roll opposing an edge of the board and cooperating means to press the board thereagainst and effective to produce in rapid recurrence during its feed of each board an increase in the pressure conditions.

2. A feed for a woodworking machine comprising, in combination with a magazine to receive a pile of boards and having an opening for the endwise discharge therefrom of the bottom board, a driven feed roll opposing an edge of the board and means operated to deliver a rapid succession of percussive blows during the feed of each board against the opposite side thereof to press it into driven relation to said roll.

3. A feed for a woodworking machine comprising, in combination with a magazine to receive a pile of boards and having an opening for the endwise discharge therefrom of the bottom board, a driven feed roll opposing an edge of the board and means operated to deliver a rapid succession of percussive blows during the feed of each board against the opposite side thereof to press it into driven relation to said roll and in a direction to exert also a feeding-out force on the board.

4. A feed for a woodworking machine comprising, in combination with a magazine to receive a pile of boards and having an opening for the endwise discharge therefrom of the bottom board, a driven feed roll opposing an edge of the board and a rotating driven member opposing the said roll having a body portion which is disposed outside of said magazine and one or more peripherally projecting portions which in its rotation intermittently enter the magazine to strike repeatedly the opposite sides of each board during its feed and to co-operate with said driven roll as a feeding couple.

5. A feed for a woodworking machine com-

prising, in combination with a magazine to receive a pile of boards and having an opening for the endwise discharge therefrom of the bottom board, driven feed rolls under-
5 riding the pile and opposing one of the edges of the bottom board and a driven feed roll opposing the opposite edge of the board, said roll being cut away whereby in one or more of its angular positions during revolution it
10 will be clear of said magazine to permit the boards of the pile successively to come into driven relation to the rolls and in other positions its peripheral portion will repeatedly strike each board in the magazine during its
15 feed and cooperate with an opposed roll as a feeding couple.

In testimony whereof, I have signed my name to this specification.
